TRAIN DISPATCHING SYSTEM FOR
RAILROADS

Richard C. Leake and Robert M. Phinney,
Rochester, N. Y., assignors to General Railway
Signal Company, Rochester, N. Y.

Application August 14, 1929, Serial No. 385,740

42 Claims. (Cl. 246—3)

This invention relates to train dispatching systems, and more particularly to synchronous selector systems of the stepping relay type.

In accordance with the present invention it is proposed to control the switch machine and the way side signals of a large railway system through the medium of a comparatively few line wires, for the purpose of dispatching the movement of trains through the medium of wayside signalling indications.

The present invention contemplates the use of neutral relays connected in chain-like fashion so that the relays of one bank may be successively picked up and again dropped in synchronism with corresponding relays of another bank. One of the features of the present invention resides in a stepping circuit in which a particular relay is adapted to be energized only if the next preceding relay has already been de-energized, this feature affording certain additional protection, in that a foreign impulse on the line which may prevent a particular relay picking up as quick as it should will cause the stepping operation to cease entirely, allowing all of the relays to assume their deenergized position. In other words, in accordance with the present invention the system is so designated that the relays will assume their deenergized position rather than follow some other stepping operation instead of the required stepping operation.

Other objects, purposes and characteristic features of the system reside in the provision of suitable means for normally keeping the apparatus at rest, initiating it when required for use and again bringing it to rest after it has been operated through a predetermined number of cycles, as well as other features which will become apparent as the description of the invention shown in the drawings progresses.

In describing the invention in detail reference will be made in the accompanying drawings, in which:—

Fig. 1A represents the apparatus in the dispatcher's office; and

Fig. 1B illustrates the apparatus located at a distant passing siding.

Referring to the drawings, it will be noted that if Figs. 1A and 1B are laid end to end the line wires are continuous, and these figures illustrate the train dispatching system of the present invention. Referring first to Fig. 1B the rails 10 of the main track of the railway system have been shown divided into sections by insulating joints 11, and also form part of a passing siding

PS including track rails 12 connected to the rails 10 through the medium of a track switch S¹ at the west end of the passing siding and a track switch S² at the east end, which track switches are in practice controlled by suitable switch machines SM¹ and SM² respectively.

The east end of passing siding PS has associated therewith a main starting signal ME, a dwarf starting signal DE, a main entering signal MW and a take-siding signal DW. The switch machine SM² is controlled by the switch machine relay SMR, and the signal ME, DE, MW, and DW are controlled by the relays SR and DR in a manner as more clearly described in the patent of S. N. Wight, Patent No. 1,889,457, dated November 29, 1932. In this connection it may be pointed out that relays MR, IR¹, IR², SR, DR and SMR are of the two position polar locking type, this locking being accomplished either by permanent magnets or by toggle springs. In the dispatcher's office (see Fig. 1A) the entire railway system is duplicated in miniature, as conventionally shown by the miniature passing siding ps. Although the present invention, as conventionally shown, includes the apparatus of a large number of passing sidings, crossovers, draw bridges and alike, together with control means therefore, for convenience the apparatus associated with the passing siding PS only has been specifically illustrated.

At the east end of this miniature passing siding ps is an indicating lamp IE, which if illuminated indicates the occupancy of the detector track circuit associated with the east end of the passing siding PS including the track relay 2T and the track battery 14, whereas the indicating lamp IW shown at the left hand of the miniature track layout is illuminated if the detector track circuit at the west end of the passing siding PS, and including the track relay IT and the track battery 15, is occupied. Similarly, there is provided in proper juxtaposition with the east end of the miniature passing siding ps a switch machine lever SML for controlling the relay SMR, and a signal lever SL which controls the distant signal relay SR and the direction relay DR.

This control of the switch machines and signals is carried out over a synchronous selector system of the stepping relay type including a stepping wire 18 and a message wire 19. This stepping wire 18 includes in series a plurality of line relays of the polar biased-to-neutral type, which specifically includes the line relay LR⁰ located at the dispatcher's office, the line relay LR¹ located at the west end of passing siding 55

PS and the line relay LR² located at the east end of the passing siding PS, the remaining line relays having, for convenience, been omitted from the drawings.

5 Associated with each of these relays LR⁰, LR¹, and LR² are the blank relays K⁰, K¹, and K² respectively, these relays only assuming their de-energized position while the line relays LR⁰, LR¹ and LR² assume their neutral biased position, 10 this being true because these relays K⁰, K¹ and K² are somewhat slow dropping and repeated reversals of the line relays will not permit these blank relays to assume their deenergized position; that is, they are deenergized only during 15 the period of blank.

At the first way station the stepping relays A¹, A², A³ and A⁴ are successively picked up in response to the repeated reversals of the line relay LR¹, providing the blank relay K² has at least 20 momentarily assumed its deenergized position just prior to these repeated reversals. Similarly, repeated reversals of the line relay LR² effects successive operation of the stepping relays B¹, B², B³ and B⁴ if once the relay B¹ has been picked 25 up due to closure of front contact 150 of relay A⁴. In the dispatcher's office the corresponding stepping relays have been designated with corresponding letters and numbers as the stepping relays of the way station, except that the number 30 precedes the letter instead of constituting an exponent to such letter. In other words, the stepping relay 1A corresponds to the stepping relay A¹, and the stepping relay 4B corresponds to the stepping relay B⁴. These dispatcher's office stepping relays 1A, 2A, 3A, 4A, 1B, 2B, 3B, 4B and 1C are operated successively in step-like fashion 35 by the line relay LR⁰, and the circuit arrangement associated with these stepping relays is such as to in turn operate the master relay MR, which master relay in turn repeatedly reverses the current flow in the stepping wire 18. In other words, the stepping relays operate the master relay MR, the master relay MR operates the line relay LR⁰ and the line relay LR⁰ in turn operates the next 40 relay of the stepping relays.

The dispatcher's office equipment also includes starting relays SR¹ and SR², indicating relays IR¹ and IR² and the relays CR and W, the function of which will be more clearly described hereinafter.

At the first way station there are also provided relays PR¹ and QR¹ for the purpose of initiating the normally at rest system after a change in track circuit occupancy takes place, the way station 2 being provided with similar relays PR² and QR². Having now pointed out the various elements of the system it is believed that their co-ordination and co-operation is best understood by considering the operation of the system.

60 *Stepping-circuit operation.*—Referring to the drawings it will be noted that each of the various relays, except the track relays 1T and 2T and relay PR¹ and PR², assume their deenergized or retracted position, and that all of the signals at the east end of the passing siding PS are at stop. Let us first consider the stepping features of the system without considering the function of the message circuit.

Let us first assume that the dispatcher for some 70 reason or other, operates the switch machine lever SML to the middle neutral position and then back to its normal full-line position. This is done in order to bring out the initiation of the system, in that such movement of the lever SML causes 75 the starting relay SR¹ to be picked up through the

completion of the following circuit:—beginning at the positive side of the battery 20, wires 21 and 22, upper winding of the relay SR², wire 23, winding of the relay SR¹, wires 24 and 25, switch blade 26 of the lever SML, wires 27 and 28 back to the negative terminal of the battery 20. The completion of this circuit not only picks up the relay SR¹ but also picks up the relay SR².

With these relay armatures in their attracted position the relay SR¹ is stuck up through the following stick circuit:—beginning at the positive side of the battery 20, wires 21 and 22, upper winding of the relay SR², wire 23, winding of the relay SR¹, wires 24 and 29, front contact 30 of the relay SR¹, wire 31, back contact 32 of the 15 stepping relay 1C, wire 33, to common return wire C connected to the negative terminal of battery 20 through wire 28. Similarly, the relay SR² is stuck up through the following stick circuit:—beginning at the positive terminal of battery 20, wires 21 and 35, winding of the relay SR², wire 36, stick contact 31 of this same relay, wire 38, through two paths in multiple including respectively the back contact 39 of the relay K⁰ and 40 of the relay CR to the wire 28 connected to the 25 negative terminal of battery 20.

With the starting relay SR² in its attracted position the following circuit for the relay CR is closed:—beginning at the terminal B of a suitable battery, front contact 42 of the relay SR², 30 wire 43, back contact 44 of the relay K⁰, wire 45, winding of the relay CR, wire 46 to the other terminal C of such battery. Energization of the relay CR completes the following pick-up circuit for the relay W:—beginning at the terminal B of 35 a suitable battery, front contact 47 of relay CR, wires 48 and 49, winding of the relay W, to common return wire C connected to the other terminal of said battery.

With the relay W in its attracted position the 40 closure of contact 50 of this relay completes the following circuit for the lower winding of the master relay MR:—beginning at the positive terminal of battery 20, wires 21 and 51, front contact 50 of relay W, wire 52, back contacts 53, 54, 55, 45 56, 57, 58, and 59, respectively of the stepping relays 1A, 2A, 3A, 4A, 1B, 2B, and 3B, wire 60, lower winding of the master relay MR, wires 62 and 63 to the negative terminal of the battery 20. The closure of this circuit, does not, however, 50 operate the master relay MR, since the completion of this circuit tends to move its contacts 64 and 65 toward the left, and since these contacts already have assumed the left-hand position they will not be changed. With the relay W now assuming its energized position the closure of the contact 67 applies current of negative polarity to the stepping wire 18, this because the contact 64 is in the left-hand position, thereby causing the line relays LR⁰, LR¹, and LR² to assume their 60 left-hand position.

Movement of the contacts 68 and 69 of the line relay LR⁰ to the left-hand position, causes the stepping relay 1A to be picked up through the following circuit:—beginning at the positive terminal of battery 20, wires 21 and 70, back contact 71 of the relay K⁰, wires 72 and 73, winding of the stepping relay 1A, wires 74 and 75, contact 68 of relay LR⁰ in its left-hand position, wire 76, winding of the relay K⁰, wire 77 to the negative terminal of battery 20. With the relay 1A once assuming its energized position the following stick circuit is closed:—beginning at the positive terminal of battery 20, wires 21, 80 and 81, stick contact 82 of relay 1A, wires 83 and 73, winding of 75

relay 1A, wires 74 and 75, contact 68 of relay LR⁰, wire 76, winding of the relay K⁰, wire 77, to the negative terminal of battery 20. It will be noted that the relay K⁰ is included in series with both 5 of the circuit for the relay 1A just traced, from which it is apparent that the relay K⁰ will presently assume its energized position and in so doing breaks the pick-up circuit of the relay 1A including the contact 71 of the relay K⁰, but the relay 10 1A will remain energized because its stick circuit is still closed.

Picking up of the relay K⁰ breaks the energizing circuit for the relay CR at the contact 44 of relay K⁰. The relay CR thus assumes its retracted 15 position, thereby again dropping its contact 85, and in so doing, bearing in mind that the relay 1A is now energized, closing the following circuit through the upper winding of the master relay MR:—beginning at the positive terminal of battery 20, wires 21 and 51, front contact 50 of relay W, wire 52, contact 53 of the relay 1A assuming its attracted position, wire 86, contact 85 of relay CR in its retracted position, wires 87 and 88, upper winding of the relay MR, wires 62 and 63, 25 back to the negative terminal of battery 20. The flow of current in this circuit causes the contact 64 and 65 of the master relay MR to be moved to their right-hand position, thereby placing current of positive polarity on to the stepping wire 30 18, and thereby operating the line relays LR⁰, LR¹ and LR² to their right-hand positions.

Also, it should be noted that even though picking up of the relay K⁰, effects de-energization of the relay CR, and opening of the pick-up circuit for relay W at contact 47, this relay W will not assume its retracted position, because it is still energized through the following stick circuit:—beginning at the terminal B, back contact 101 of the stepping relay 1C, wire 102, front contact 103 of the relay K⁰, wire 104, stick contact 105 of relay W, wires 106 and 49, winding of the relay W, to common return wire connected to the other terminal of said battery. It is thus seen that the relay W will remain energized until the last relay 45 in the stepping relay series has assumed its energized position and has opened the stick circuit of relay W at the contact 101. In other words, the stepping circuit remains closed at the contact 67 of relay W until the stepping operation 50 has proceeded through the entire bank of stepping relays.

It should be noted that shifting of the contact 68 from its left-hand to its right-hand position breaks the energizing circuit for the relay 1A, but before this relay 1A can assume its retracted position the relay 2A has been picked up through the following circuit:—beginning at the positive terminal of battery 20, wires 21 and 80, front contact 90 of the relay 1A, wires 91 and 92, winding of the relay 2A, wires 93 and 95, contact 68 of the relay LR⁰, wire 76, winding of the relay K⁰, wire 77, to the negative terminal of battery 20, thus causing the relay 2A to be picked up. With the relay 2A in its attracted position the following stick circuit for this relay is closed:—beginning at the positive terminal of battery 20, wires 21, 20, 97, and 98, stick contact 99 of the relay 2A, wires 100 and 92, winding of the relay 2A, wires 93 and 95, contact 68 of relay LR⁰, wires 76, winding of relay K⁰, winding 77 to the negative terminal of battery 20.

With the relay 2A assuming its attracted position, the contact 54 is lifted, but this lifting of contact 54 does not effect the application of cur-

rent to the master relay MR until the contact 53 of relay 1A has assumed its retracted position, at which time the following circuit for the lower winding of the master relay MR is closed:—beginning at the positive terminal of battery 20, wires 21 and 51, contact 50 of relay W, wire 52, back contact 53 of relay 1A, front contact 54 of relay 2A, wire 60, bottom winding of the master relay MR, wires 62 and 63 to the negative terminal of battery 20. Completion of this circuit effects operation of the master relay MR to the left-hand position, thereby applying polarity of negative current to the stepping circuit, and operating the various line relays LR⁰, LR¹ and LR² to the left-hand position.

With the line relay LR⁰ in its left-hand position, the stepping relay 2A is de-energized, but before it can assume its de-energized position the stepping relay 3A is energized through the following circuit:—beginning at the positive terminal of battery 20, wires 21, 80, and 108, front contact 109 of relay 2A, wires 110 and 111, winding of the relay 3A, wire 112 and 75, contact 68 of relay LR⁰, wire 76, winding of relay K⁰, wire 77, to the negative terminal of battery 20. The relays 4A, 1B, 2B, and 3B are successively picked up through the pick-up circuit and stuck up through stick circuits which are analogous to the pick-up circuit for the relays 3A so that the circuits for relays 4A, 1B, 2B, and 3B need not be specifically traced, it being deemed sufficient to trace the stick circuit for the relay 3B. This stick circuit may be traced as follows:—beginning at the positive terminal of battery 20, wires 21, 80, 114 and 115, stick contact 116 of the relay 3B, wires 117 and 118, winding of the relay 3B, wires 119 and 75, contact 68 of the relay LR⁰, wire 76, winding of the relay K⁰, wire 77, to the negative terminal of battery 20.

With this relay 3B energized and the relay 2B deenergized, current is shifted from the lower to the upper winding of the relay MR through a circuit readily traced in the drawings including contact 58 of relay 2B in its retracted position and contact 59 of relay 3B in its attracted position. The completion of this circuit causes the master relay MR to be moved to the right thereby applying positive current to the stepping circuit and effecting operation of the line relays LR⁰, LR¹, and LR² to the right. This in turn causes the relay 4B to be picked up and the relay 3B to be dropped. Dropping of the relay 3B again shifts the current from the upper winding to the lower winding of the master relay MR, thereby causing the line relays LR⁰, LR¹ and LR² to be operated to the left, which causes the stepping relay 1C to be energized through its pick-up circuit including front contact 113 of the relay 4B. With the relay 1C once energized its back contact 101 is opened and the stick circuit for the relay W is broken, thereby effecting de-energization of the relay W. With the relay W deenergized the stepping circuit is opened at the contact 67 of this relay W, thereby preventing any further operation of the line relays LR⁰, LR¹ and LR², and in fact causing their contacts to assume their middle-biased open position, which effects de-energization of the stepping relay 1C because its energizing circuit is broken at contact 68 of relay LR⁰. However, while the relay 1C assumes its energized position, the stick circuit for the starting relay SR¹ at the contact 32 of the relay 1C is broken, so that the starting relay SR¹ assumes its deenergized position.

The starting relay SR², however, remains in 75

its energized position and as soon as the slow-acting blank relay K^0 assumes its retracted position in response to the pendant position of contact 68 of line relay LR^0 , the energizing circuit for the relay CR is again closed at the back contact 44 of relay K^0 . Obviously, with the relay CR again energized the relay W is caused to be energized, and its closure of the contact 67 causes negative current to again be applied to the stepping line wire 18. In this connection attention is directed to the fact that even though negative current is applied to the stepping wire twice in succession at this point in the operation, namely for the purpose of picking up the relay 1C, as heretofore described, and now for the purpose of picking up the relay 1A, this distinctive picking up of relays 1C and 1A is dependent upon the conditions of relays K^0 and 4B. In this connection it should be remembered that the relay 4B was in its energized position when the relay 1C was picked up and the relay K^0 was in its energized position, whereas at the time now under consideration the relay 4B is deenergized and the relay K^0 assumes its deenergized position. Obviously the same cycle of operation of the stepping relays as heretofore described will now be repeated in that the cycle of operation has been re-initiated in response to the picking up of the relay CR.

Attention is directed at this time to the fact that the picking up of the relays CR and K^0 in each case broke the stick circuit for the starting relay SR^2 at the contact 40 of relay CR and the contact 39 of relay K^0 . This starting relay SR^2 in the first instant did not assume its deenergized position because it was held up by current flow in the upper winding of the relay SR^2 . The second picking up of the relays CR and K^0 however effect deenergization of the relay SR^2 , because the relay SR^2 is no longer assuming its energized position and consequently there is no current flow in the upper winding of the relay SR^2 and since the stick circuit of relay CR² has now been opened at the contacts 40 and 39 (in multiple) of the relays CR and K^0 , the relay SR^2 will also assume its deenergized or retracted position, so that the third cycle of operation will not take place unless the relays SR^1 and SR^2 are again picked up in response to the movement of a lever, or a change in the occupancy of a detector track circuit in a manner as more clearly pointed out hereinafter. This construction (contacts 39 and 40 in multiple) is resorted to to assure that the relay SR^2 does not drop until the entire starting function is complete, that is relay CR and K^0 have both been picked up.

Referring now to the wayside equipment and bearing in mind that the first application of negative current to the stepping wire effected picking up of the relay 1A in the dispatcher's office, let us observe how the companion-stepping relay A¹ is picked up in response to the first application of current of negative polarity to the line relay LR^1 . This application of current of negative polarity to the line relay LR^1 causes energy to be applied to the slow-acting blank relay K^1 , but before this relay K^1 has time to assume its energized position, the relay A¹ is picked up through the following pick-up circuit:—beginning at the positive terminal of the battery 120, wires 121 and 122, back contact 123 of the relay K^1 , wires 124 and 125, winding of the relay A¹, wires 126 and 127, contact 128 of the relay LR^1 assuming its left-hand position, wire 129 and 130, to the negative

terminal of the battery 120. The relay K^1 , assumes its energized position a moment later, and in response to the closure of the following circuit:—beginning at the positive terminal of battery 120, wire 121, contact 131 of relay LR^1 assuming its left-hand position, wire 132, winding of the relay K^1 , wire 133, wire 130, to the negative terminal of battery 120. Attention is directed to the fact that the circuit just traced is closed when the line relay LR^1 assumes either the right-hand or left-hand position, so that this relay K^1 remains in its attracted position so long as the line relay LR^1 is reversed at the usual normal stepping rate. As soon as the stepping relay A¹ assumes its attracted position the following stick circuit for this relay is closed:—beginning at the positive terminal of battery 120, wires 121 and 135, stick contact 136 of relay A¹, wires 137 and 125, winding of the relay A¹, wires 126 and 127, contact 128 of line relay LR^1 , wires 129 and 130 to the negative terminal of battery 120.

It thus appears that the relay A¹ is picked up synchronously with the relay 1A through the means of circuits and devices substantially identical to that used for picking up of this companion relay 1A. Similarly, with the relay A¹ assuming its attracted position and with the line relay LR^1 operated to the right, the relay A² is picked up through the following pick-up circuit:—beginning at the positive terminal of battery 120, wires 121 and 138, front contact 139 of relay A¹, wires 140 and 141, winding of the relay A², wires 142, and 143, contact 128 of the line relay LR^1 , wires 129 and 130 to the negative terminal of battery 120. With the relay A² once energized its stick circuit including its stick contact 144 is closed.

Similarly, the relay A² is picked up through the front contact 145 of the relay A² and is then stuck up through its stick contact 146 with the line relay LR^1 in its left-hand position. Further, the stepping relay A⁴ is picked up through the front contact 147 of the relay A³ and is then stuck up through the stick contact 148 of the relay A⁴ with the line relay LR^1 assuming its right-hand position.

Movement of the line relay LR^2 to the left-hand position remembering that relay A⁴ is still energized, completes the following pick-up circuit for the stepping relay B¹:—beginning at the positive terminal of the battery 120, back contacts 139, 145 and 147 of the stepping relays A¹, A², and A³, respectively, front contact 150, of the relay A⁴, line wire 151, extending from the west end of passing siding PS to the east end of this passing siding PS, wire 152, winding of the relay B¹, wires 153 and 155, contact 156 of the line relays LR^2 in its left-hand position, wires 157 and 158 to the common return wire C connected to the negative terminal of the battery 120. It is thus seen that the relay B¹ is picked up in synchronism with the relay 1B.

With the relay B¹ now energized movement of the contacts of line relay LR^2 to the right-hand position effects deenergization of the relay B¹, but before this relay B¹ can assume its retracted position the following pick-up circuit is closed for the stepping relay B²:—beginning at the positive terminal of the battery 220, wires 160 and 161, front contact 162 of the relay B¹, wires 163 and 164, winding of the relay B², wires 165 and 166, contact 156 of the line relay LR^2 , wires 157 and 158, to the negative terminal of battery 220. With the relay B² once energized its stick circuit including the front stick contact 167 of this relay is picked up and its stick circuit is closed.

Similarly, movement of the contact 156 of line relay LR² to the left with the relay B² energized, the relay B³ is picked up through a circuit including the front contact 168 of relay B², and with 5 the relay B³ once picked up it is stuck up through a circuit including its stick contact 169.

Similarly, with the relay B³ energized and the line relay LR² then shifted to the right, the relay B⁴ is picked up through the front contact 170 of 10 the relay B³. Before this relay B³ however actually assumes its retracted position the relay B⁴ is stuck up through a stick circuit including its front contact 171, after which shifting of contact 156 of the line relay LR², to the left, opens the stick 15 circuit for the relay B⁴, and causes this relay B⁴ to assume its retracted position. In the meantime, however, the first relay of another group of 20 relays (not shown) may be picked up through the contact 172 of the relay B⁴, if such another group of stepping relays is employed.

We have now pointed out how the system initiated and how it will run through two complete cycles of operation and will then be brought to stop, and how the stepping relays 1A, 2A, 3A, 4A, 25 1B, 2B, 3B, and 4B are picked up synchronously with the corresponding stepping relays A¹, A², A³, A⁴, B¹, B², B³, and B⁴, respectively. With this understanding of the system it is believed expedient to consider lever operation and train movement, and observe how a large number of message 30 circuits may be sequentially closed to obtain distinctive controls over a comparatively few line wires.

Message-circuit operation.—Let us assume that 35 the dispatcher wishes to move the track switch S² to the take-siding position in order to accomplish this movement of the switch S² he will move his lever SML to the right hand position and in so doing will momentarily close the contacts 26, thereby effecting energization of the starting relays SR¹ and SR² and effecting initiation of the system, in a manner as described in detail in the foregoing description. This initiation of the system causes the stepping relays in 40 the dispatcher's office and the companion stepping relays at the way stations to be synchronously operated to their attracted position and back to their retracted position, until eventually the stepping relay 3B and the stepping relay B³ will 45 momentarily assume their energized position simultaneously, and when this occurs this relay SMR is operated to its left-hand position through completion of the following message circuit:—beginning at the negative terminal of a suitable battery, such as the battery 41, contact 175 of the lever SML, wire 176, front contact 177 of the stepping relay 3B, back contacts 178, 179, 180, 181, 182, and 183 of the relays 2B, 1B, 4A, 3A, 2A, and 1A, respectively, wire 184, contact 69 in its 50 left-hand position, wire 185, contact 65 of the master relay MR in its right-hand position, wire 186, contact 187 of the relay K⁰ in its attracted position, message wire 19, wire 188 (see Fig. 1B), front contact 189 of the relay K², wire 190, back 55 contacts 191 and 192 of the relays B¹ and B², respectively, front contact 193 of the relay B³, wire 194, winding of the switch machine relay SMR, to common return wire C connected to the midpoint of battery 41. The completion of this message circuit causes the switch machine relay SMR to be moved to the left-hand position, thereby operating the switch machine SM² to its take-siding position, providing of course that traffic conditions are such that the switch machine can 60 be operated with safety, suitable approach lock- 65

ing means being used for this purpose. The synchronous stepping relay system will operate through two complete cycles of operation at which time the starting relays SR¹ and SR² will again have assumed their de-energized position 5 and therefore will not reinitiate the system.

Attention is directed to the fact that this message circuit, as well as all other message circuits, include contacts 65 and 69 of relays MR and LR⁰, respectively, assuming opposite positions. This 10 expedient is resorted to, because it is desirous to cut down the time during which the message circuit may be completed, this in order to avoid possible overlap between two otherwise distinct message circuits. In other words, this expedient is 15 employed to avoid a particular lever operating the wrong relay at the distant point, bearing in mind that it is possible for two adjacent stepping relays to be energized in slightly overlapped relation. 20

Let us now assume that there is a train standing on the side track of passing siding PS, and that this is an east bound train and moves over the switch S² in response to clearing of the dwarf signal DE. The treading of this train upon the 25 detector track circuit including the track relay 2T, will cause this track relay 2T to be de-energized, thereby causing the relay QR² to be picked up through the following circuit:—beginning at the terminal B, contact 200, of the relay 2T in its 30 retracted position, wire 201, contact 202, of the relay PR², which relay is slow-dropping and has not yet assumed its de-energized position, wires 203 and 204, winding of the relay QR², to the other terminal C of said battery. 35

With this relay QR² energized the starting relay SR¹ is energized, during the at-rest period of the synchronous selector system, through the following circuit:—beginning at the positive terminal of battery 20, wires 21 and 22, upper winding of the relay SR², wire 23, winding of the relay SR¹, wires 24 and 205, back contact 187 of the relay K⁰, message wire 19, wire 188, back contact 189 of the relay K², wire 207, front contact 208 of the relay QR², wire 209, back to the battery 20 40 through the medium of the common return wire C. It is thus seen that the synchronous selector system is initiated in response to dropping of the track relay 2T. Attention is directed to the fact that had the relay 2T assumed its retracted position during a cycle of operation of the synchronous selector system, the front contact 210 of the slow-acting relay K² would have been closed, thus closing the following stick circuit for the relay QR²:—beginning at B, front contact 210 of relay K², wire 211, stick contact 212, wire 213 and 204, winding of the relay QR² to the other terminal C. From this it appears that the relay QR² would remain stuck up during the cycle of operation then being consummated, and upon completion of such cycle the dropping of the contact 45 50 55 60 65 70 75 ing function to the message transmitting function, and vice versa.

The track relay **2T** now being in its retracted position causes negative current to flow from the battery **225** through the following message circuit completed momentarily while the stepping relays **4B** and **B⁴** simultaneously assume their attracted position:—beginning at the negative terminal of battery **225**, contact **226** of relay **2T** in its retracted position, contact **227** of the relay **B⁴** in its attracted position, contacts **193**, **192**, and **191** of the relays **B³**, **B²**, and **B¹**, respectively, in their retracted positions, wire **190**, front contact **189** of the slow-acting relay **K²**, wire **188**, message wire **19**, contact **187** of the relay **K⁰** in its attracted position, wire **186**, contact **65** of the master relay **MR** in its left-hand position, wire **228**, contact **69** of the relay **LR⁰** in its right-hand position, wire **184**, contacts **183**, **182**, **181**, **180**, **179**, **178**, and **177** of the relay **1A**, **2A**, **3A**, **4A**, **1B**, **2B**, and **3B**, respectively, all in their retracted position, contact **229** of the stepping relay **4B** in its attracted position, wire **230**, indicating relay **IR²**, wires **231** and **28**, common return wire **C**, and wire **232** connected to the midpoint of battery **225**.

Similarly, deenergization of the track relay **1T** causes the following message circuit to be completed while the stepping relay **4A** and **A⁴** simultaneously assume their energized position:—beginning at the negative terminal of battery **235**, contact **236** of the track relay **1T** in its retracted position, contact **237** of the relay **A⁴** in its attracted position, contacts **238**, **239** and **240** of the relay **A³**, **A²**, and **A¹**, respectively, all assuming their retracted position, wire **241**, front contact **242** of the relay **K¹**, wire **243**, message wire **19**, contact **187** of the relay **K⁰** in its attracted position, wire **186**, contact **65** of the master relay **MR** in its left-hand position, wire **228**, contact **69** of the line relay **LR⁰** in its right-hand position, wire **184**, back contacts **183**, **182**, and **181** of the stepping relay **1A**, **2A**, and **3A**, respectively, contact **180** of the stepping relay **4A** in its attracted position, wire **244**, winding of the relay **IR¹**, wire **245**, common return wire **C**, and wire **246** connected to the midpoint of battery **235**.

It has just been pointed out how the relay **QR²** is stuck up upon dropping of the track relay **2T** while the blank relay **K²** is energized. Let us now observe how this relay **QR²** is stuck up due to picking up of the track relay **2T** while the blank relay **K²** is energized. Under the conditions assumed the relays **QR²**, **PR²** and **2T** assume their deenergized positions and the relay **K²** assumes its attracted position. If now the track relay **2T** is picked up, by reason of the fact that the train in question has moved off of this detector track circuit, the following pick-up circuit for the relay **QR²** is momentarily closed:—starting at **B**, front contact **200** of the track relay **2T**, wires **260** and **261**, contact **292** of the relay **PR²** in its retracted position, wires **203** and **204**, winding of the relay **QR²**, to the return wire **C**. This relay **QR²** will then be stuck up through the stick circuit herefore traced. From this it appears that the system is also restarted in response to the picking up of the track relay **2T** irrespective of whether such picking up of the track relay **2T** occurs when the synchronous selector system is at rest or is operating at an intermediate point in a cycle of operation.

Let us now assume that the dispatcher wishes to clear the main starting signal **ME** at the east end of the passing siding **PS**. In order to do this he will move his signal lever **SL** to the right-

hand position, thereby closing the following two-message circuits for the relays **SR** and **DR** when the relays **1B**—**B¹** and **2B**—**B²**, respectively, assume momentary energized positions:—(1) beginning at the terminal **B**— of a suitable battery such as battery **41**, contact **248** of the signal lever **SL**, wire **249**, contact **179** of relay **1B** in its attracted position, contacts **180**, **181**, **182** and **183** of the relays **4A**, **3A**, **2A** and **1A**, respectively, all assuming their retracted position, wire **184**, contact **69** of relay **LR⁰** in its left-hand position, wire **185**, contact **65** of relay **MR** in its right-hand position, wire **186**, front contact **187** of relay **K⁰**, message wire **19**, wire **188** (see Fig. 1B), contact **189** of the relay **K²** in its attracted position, wire **190**, contact **191** of the relay **B¹** in its attracted position, wire **250**, winding of the relay **SR** to common return wire **C** connected to the midpoint of battery **41**; and, (2) beginning at the terminal **B**— of the same battery **41**; contact **251** of the signal lever **SL** in its right-hand position, wire **252**, contact **178** of the relay **2B** in its attracted position, contacts **179**, **180**, **181**, **182**, **183** of the relays **1B**, **4A**, **3A**, **2A** and **1A**, respectively, all assuming their retracted position, wire **184**, contact **69** of relay **LR⁰** assuming its right-hand position, wire **228**, contact **65** of relay **MR** in its left-hand position, wire **186**, contact **187** of the relay **K⁰** in its attracted position, message wire **19**, wire **188** (see Fig. 1B) contact **189** of relay **K²** in its attracted position, wire **190**, contact **191** in its retracted position, contact **192** of relay **B²** in its attracted position, wire **253**, winding of the direction relay **DR**, to common return wire **C** connected to the midpoint of battery **41** in the dispatcher's office. The completion of these two message circuits just traced, each of which lead from the positive terminal of the battery **41**, cause the relays **SR** and **DR** to be operated to their right-hand positions, but since the direction relay **DR** is already in its right-hand position, this relay will not be operated. The relay **SR**, on the other hand, will be operated to the right to a position to clear the signal **ME**, this because the direction relay **DR** is to the right and the switch machine relay **SMR** is to the right. Clearing of signal **ME** signifies movement of east bound traffic over the main track.

Referring to Fig. 1B of the drawings it will be noted that the relay **B¹** is picked up through a line wire **151** extending from the west end of the passing siding **PS** to the east end of the passing siding. In some cases the distance from one way station to the next way station is so great that it may be desirable to omit this line wire **151**. In this case the relay such as relay **B¹**, will be operated by a number of impulse counting or absorbing relays corresponding to the stepping relays of all the preceding way stations. In other words, in the case under consideration if the line wire **151** were omitted the relay **B¹** would be preceded by four stepping relays located near and controlled by the line relay **LR²** and the slow-acting relay **K²** in exactly the same manner as are the relays **A¹**, **A²**, **A³**, and **A⁴**. Similarly, there may be many other variations in the exact construction of the system disclosed, for instance, any number of channels may be provided for a particular way station to obtain additional functions, such as indicating of the occupancy of the main track of the passing siding or over the side track thereof. Further, any other suitable means may be substituted for the relays **PR²** and **QR²** in order to assure initiation of this system after a change in occupancy.

of a detector track circuit, or a change in any other traffic condition. Also, if desired the system may be one of the continuously operating type by omitting the stopping and initiating mechanism. For instance, the position of the switch machines may be indicated by suitable indicating lamps in the dispatcher's office in exactly the same manner as detector circuit occupancy is indicated, in which event the system would be initiated if the switch machine is cranked by hand, so that the changed position of the switch machine would be manifested in the dispatcher's office. In other words, many of the sub-combinations of the entire system may be replaced by devices having similar functions without changing the ultimate result in the operation of the system and without departing from the present invention.

Having thus shown and described one rather specific embodiment of the present invention, it is desired to be understood that the particular circuit arrangement selected to illustrate an embodiment of the present invention has been selected for the purpose of facilitating disclosure of the underlying principles of the present invention as well as its operating characteristics, and not been selected with the intent of showing the exact construction preferably employed in practicing the invention or its scope, and that various changes, additions and modifications may be made to the specific construction shown, without departing from the spirit or scope of the invention or the idea of means underlying the same, except as demanded by the scope of the following claims.

What we claim as new is:—

1. In a train dispatching system of the synchronous selector type, the combination with a local dispatcher's office and a distant way station; a stepping wire and a common return wire connecting said office and way station; and means for applying potential of positive polarity, potential of negative polarity or no potential between said stepping wire and said common wire comprising; a two position polar relay of the locking type for connecting the positive or the negative terminal of a split battery to the stepping wire, and a neutral relay having its front contact included in said stepping wire; whereby said neutral relay determines whether or not potential shall be applied to the stepping circuit and said polar relay determines the polarity of said potential.

2. In a train dispatching system of the synchronous selector type, the combination with a local dispatcher's office and a distant way station; a stepping wire and a common return wire connecting said office and way station; and means for applying potential of positive polarity, potential of negative polarity or no potential between said stepping wire and said common wire comprising; a two position polar relay of the locking type for connecting the positive or the negative terminal of a split battery to the stepping wire, and a neutral relay having its front contact included in said stepping wire; whereby said neutral relay determines whether or not potential shall be applied to the stepping circuit and said polar relay determines the polarity of said potential, a pick-up and a stick circuit for said neutral relay, means for momentarily closing said pick-up circuit to initiate said system, and means for momentarily breaking said stick circuit at one point at the end of a complete cycle of operation of said system.

3. In a train dispatching system of the synchronous selector type, the combination with a local dispatcher's office and a distant way station; a stepping wire and a common return wire connecting said office and way station; and means for applying potential of positive polarity, potential of negative polarity or no potential between said stepping wire and said common wire comprising; a two position polar relay of the locking type for connecting the positive or the negative terminal of a split battery to the stepping wire, and a neutral relay having its front contact included in said stepping wire; whereby said neutral relay determines whether or not potential shall be applied to the stepping circuit and said polar relay determines the polarity of said potential, of a pick-up and a stick circuit for said neutral relay, means for momentarily closing said pick-up circuit to initiate said system, means for momentarily breaking said stick circuit at one point at the end of a complete cycle of operation of said system, and means for alternately operating said polar relay to its right-hand and left-hand position so long as said neutral relay is energized.

4. Dispatcher's office equipment for train dispatching systems of the synchronous selector type comprising, an out-going stepping line including a line relay in series therewith, a master relay of the two-position locking type for applying positive potential to said stepping line when in one position and applying negative potential to said stepping line when in its other position, a starting relay having a front contact included in said stepping line, whereby said stepping line is deenergized when said starting relay is deenergized, and means for energizing said starting relay to initiate said system and for deenergizing said starting relay at the end of each cycle.

5. Dispatcher's office equipment for train dispatching systems of the synchronous selector type comprising, an out-going stepping line including a line relay in series therewith, a master relay of the two-position locking type for applying positive potential to said stepping line when in one position and applying negative potential to said stepping line when in its other position, a starting relay having a front contact included in said stepping line, whereby said stepping line is deenergized when said starting relay is deenergized, a control lever, starting means for picking up said starting relay when the position of said control lever is changed, and a stick circuit for said starting relay broken momentarily at the end of each cycle of operation of the system.

6. Dispatcher's office equipment for train dispatching systems of the synchronous selector type comprising, an out-going stepping line including a line relay in series therewith, a master relay of the two-position stick type for applying positive potential to said stepping line when in one position and applying negative potential to said stepping line when in its other position, a starting relay having a front contact included in said stepping line, whereby said stepping line is deenergized when said starting relay is deenergized, a control lever, starting means for picking up said starting relay when the position of said control lever is changed, a stick circuit for said starting relay broken momentarily at the end of each cycle of operation of the system, and means including said starting means for again picking up said starting relay a moment after it has assumed its deenergized position at the end of the

first cycle of operation of the movement of said lever.

7. Way station apparatus for train dispatching systems of the synchronous selector type comprising, a line relay of the three-position type operated alternately to one and then to other of its energized positions during a cycle of operation of the system and assuming the deenergized position during the period of blank between successive cycles, a slow-acting relay, energizing circuits for said slow-acting relay closed when said line relay assumes either of its energized positions, whereby said slow-acting relay is deenergized only during said period of blank, a series of stepping relays, a pick-up circuit for the first stepping relay including a back contact of said slow-acting relay and the reverse contact of said line relay, and a pick-up circuit for the second stepping relay including a front contact 20 of the next preceding stepping relay and the normal contact of said line relay.

8. Way station apparatus for train dispatching systems of the synchronous selector type comprising, a line relay of the three-position type operated alternately to one and then to the other of its energized positions during a cycle of operation of the system and assuming the deenergized position during the period of blank existing between successive cycles, a slow-acting relay, energizing circuits for said slow-acting relay closed when said line relay assumes either of its energized positions, whereby said slow-acting relay is deenergized only during said period of blank, a series of stepping relays, a pick-up circuit for 35 the first stepping relay including a back contact of said slow-acting relay and a circuit for the second stepping relay including a front contact of the next preceding stepping relay and the normal contact of said line relay, and a stick circuit for each of said stepping relays including the same contact of said line relay as is included in the pick-up circuit of said stepping relay.

9. In a synchronous selector train dispatching system of the normally-at-rest type which includes a message wire and a common wire and which system is initiated from rest in response to connecting the message wire to said common wire, means for connecting said message wire to said common wire at the end of a cycle of operation of said system in response to a change in the position of a track relay even though such change takes place during the cycle period when the message wire must not be connected to said common wire comprising; a stick relay, a slow-acting relay, circuits for maintaining said slow-acting relay energized during the complete cycle of operation of the system and for deenergizing said slow-acting relay during a period of blank, and a shorting branch circuit connecting said message wire and common wire including a back contact of said slow-acting relay and a front contact of said stick relay.

10. In a synchronous selector train dispatching system of the normally-at-rest type which includes a message wire and a common wire and which system is initiated from rest in response to connecting the message wire to said common wire, means for connecting said message wire to said common wire at the end of a cycle of operation of said system in response to a change in the position of a track relay contact even though such change takes place during the cycle period when the message wire must not be connected to said common wire comprising; a stick relay, a slow-acting relay, circuits for maintaining said slow-

acting relay energized during the complete cycle of operation of the system and for deenergizing said slow-acting relay during a period of blank, a shorting branch circuit connecting said message wire and common wire including a back contact 5 of said slow-acting relay and a front contact of said stick relay, a pick-up circuit for said stick relay and a stick circuit for said stick relay including a front contact of said slow-acting relay.

11. In a synchronous selector train dispatching system of the normally-at-rest type which includes a message wire and a common wire and which system is initiated from rest in response to connecting the message wire to said common wire, means for connecting said message wire to said common wire at the end of a cycle of operation of said system in response to a change in the position of a track relay even though such change takes place during the cycle period when the message wire must not be connected to said common wire comprising; a stick relay, a slow-acting relay, circuits for maintaining said slow-acting relay energized during the complete cycle of operation of the system and for deenergizing said slow-acting relay during a period of blank, a 10 shorting branch circuit connecting said message wire and common wire including a back contact of said slow-acting relay and a front contact of said stick relay, a second slow-acting relay, two pick-up circuits for said stick relay one including 15 a front contact of such track relay and a back contact of said second slow-acting relay and the other of which includes a back contact of such track relay and a front contact of said second slow-acting relay, and an energizing circuit for 20 said second slow-acting relay including a front contact of such track relay.

12. In a synchronous selector train dispatching system of the normally-at-rest type which includes a message wire and a common wire and which system is initiated from rest in response to connecting the message wire to said common wire, means for connecting said message wire to said common wire at the end of a cycle of operation of said system in response to a change in the 45 position of a track relay even though such relay change takes place during the cycle period when the message wire must not be connected to said common wire comprising; a stick relay, a slow-acting relay, circuits for maintaining said slow-acting relay energized during the complete cycle of operation of the system and for de-energizing 50 said slow-acting relay during a period of blank, a shorting branch circuit connecting said message wire and common wire including a back contact of said slow-acting relay and a front contact of said stick relay, a second slow-acting relay, two pick-up circuits for said stick relay one including 55 a front contact of such track relay and a back contact of said second slow-acting relay and the other of which includes a back contact of such track relay and a front contact of said second slow-acting relay, an energizing circuit for said second slow-acting relay including a front contact of such track relay, and a stick circuit for said 60 stick relay including its own stick contact and a front contact of said first-mentioned slow-acting relay.

13. In a centralized traffic controlling system of the normally at rest selector type, the combination with a selector system normally at rest and provided with a stepping circuit having impulses impressed thereon when the system is in operation, of means for starting said system comprising, a stick relay having a front contact which 75

if closed starts said system, an indicating contact for manifesting traffic conditions, a slow acting repeater relay for repeating the position of said indicating contact, a pick-up circuit for said stick relay closed only when said indicating contact and said repeater relay are out of correspondence, and a stick circuit for said stick relay including a contact controlled in response to impulses on said stepping circuit.

10 14. In a centralized traffic controlling system, the combination with a stepping line and a message line connecting a central office and a distant way station, normal-at-rest selector apparatus at said office and said way station, a slow acting relay at said office and way station energized upon intermittent energization of said stepping line, a front contact on each of said slow acting relays for rendering said selector apparatus responsive to impulses on said stepping circuit, and a back contact on each of said slow acting relays for initiating the system through said message circuit to apply impulses to said stepping line.

15 15. In a centralized traffic controlling system, the combination with a stepping line and a message line connecting a central office and a distant way station, normal-at-rest selector apparatus at said office and said way station, a slow acting relay at said office and way station energized upon intermittent energization of said stepping line, a front contact on each of said slow acting relays for rendering said selector apparatus responsive to impulses on said stepping circuit, a back contact on each of said slow acting relays for initiating the system through said message circuit to apply impulses to said stepping line, and another front contact on said slow acting relays included in said message circuit for transmitting control impulses over said message circuit.

20 16. In a centralized traffic controlling system of the selector type for railroads, the combination with a central office and a plurality of way stations, a selector circuit connecting said office and way stations, a line relay in said selector circuit at each way station, means in said central office for intermittently energizing said selector circuit to control apparatus at one of said way stations, a normally deenergized slow acting relay at each way station energized by each intermittent energization of said selector circuit through the medium of the line relay at such way station and sufficiently slow dropping to remain in its attracted condition until the next energization of said selector circuit, whereby the fact whether said slow acting relay assumes its energized or its deenergized condition manifests when intermittent energization of said selector circuit begins and ceases, a series of counting relays at each way station successively energized by the associated line relay, and an initiating circuit for the control of said counting relays including a back contact of said slow acting relay.

25 17. In a centralized traffic controlling system of the selector type for railroads, the combination with a central office and a plurality of way stations, a selector circuit connecting said office and way stations, a line relay in said selector circuit at each way station, means in said central office for intermittently energizing said selector circuit to control apparatus at one of said way stations, a slow acting relay at each way station energized by each intermittent energization of said selector circuit through the medium of the line relay at such way station and

sufficiently slow dropping to remain in its attracted condition until the next energization of said selector circuit, whereby the fact whether said slow acting relay assumes its energized or its deenergized condition manifests when intermittent energization of said selector circuit begins and ceases, said system being normally at rest, and an initiating circuit for starting said system including a contact of such slow acting relay.

30 18. In a centralized traffic controlling system of the selector type for railroads, the combination with a central office and a plurality of way stations, a selector circuit connecting said office and way stations, a line relay in said selector circuit at each way station, means in said central office for intermittently energizing said selector circuit to control apparatus at one of said way stations, a slow acting relay at each way station energized by each intermittent energization of said selector circuit through the medium of the line relay at such way station and sufficiently slow dropping to remain in its attracted condition until the next energization of said selector circuit, whereby the fact whether said slow acting relay assumes its energized or its deenergized condition manifests when intermittent energization of said selector circuit begins and ceases, a storing relay of the stick type which is picked up when the system should be re-initiated, and a stick circuit for said storing relay including a front contact of said slow acting relay.

35 19. In a centralized traffic controlling system of the selector type for railroads, the combination with a central office and a plurality of way stations, a selector circuit connecting said office and way stations, a line relay in said selector circuit at said office and at each way station, means in said central office for intermittently energizing said selector circuit to control apparatus at one of said way stations, and a slow acting relay at said office and at each way station energized during each intermittent energization of said selector circuit through the medium of the line relay at said office and sufficiently slow dropping to remain in its attracted condition until the next energization of said selector circuit, whereby the energized and deenergized condition of said slow acting relays manifest respectively whether or not said selector circuit is intermittently energized.

40 20. In a centralized traffic controlling system of the selector type for railroads, the combination with a central office and a plurality of way stations, a selector circuit connecting said office and way stations, a line relay in said selector circuit at said office and at each way station, means in said central office for intermittently energizing said selector circuit to control apparatus at one of said way stations, a slow acting relay at said office energized during each intermittent energization of said selector circuit through the medium of the line relay at said office and sufficiently slow dropping to remain in its attracted condition until the next energization of said selector circuit, whereby the energized and deenergized condition of said slow acting relay manifests respectively whether or not said selector circuit is intermittently energized, a series of counting relays at said office, and an initiating circuit for the control of said counting relays including a contact of said slow acting relay.

45 21. In a centralized traffic controlling system of the selector type for railroads, the combination with a central office and a plurality of way

stations, a selector circuit connecting said office and way stations, a line relay in said selector circuit at said office and at each way station, means in said central office for intermittently energizing said selector circuit to control apparatus at one of said way stations, a slow acting relay at said office energized during each intermittent energization of said selector circuit through the medium of the line relay at said office and sufficiently slow dropping to remain in its attracted condition until the next energization of said selector circuit, whereby the energized and deenergized condition of said slow acting relay manifests respectively whether or not said selector circuit is intermittently energized, said system being normally at rest, and an initiating circuit for said system including a contact of said slow relay.

22. In a traffic controlling system for railroads, the combination with electrically operated means operable to impress a plurality of electrical current impulses on the stepping circuit of the selector system, a cycle demarking relay which assumes its energized position on the first of such impulses and remains energized until the end of the last impulse, a series of stepping relays the first of which can only be picked up if the cycle demarking relay is at that time deenergized and the others of which can only be picked up if the next preceding relay is up, and the proper kind of impulse is impressed on the stepping circuit, and means for transmitting a control impulse when a particular one of said stepping relays is assuming its energized position.

23. A centralized traffic controlling system comprising in combination, a line circuit, means for selectively applying positive or negative energy to said line circuit, a polar line relay having contacts capable of assuming either of two positions in accordance with the polarity of the energy applied to said line circuit, a neutral relay, an energizing circuit closed for said neutral relay when the contacts of said polar relay assume either of their positions, stepping relay means, and a circuit for initiating said relay means controlled in accordance with the position assumed by the contacts of said polar relay during the pick-up period of said neutral relay.

24. A centralized traffic controlling system comprising in combination; a line circuit; a polar line relay included in said line circuit, said relay having contacts operable to either of two polar positions in accordance with the polarity of the energization of said line circuit; a slow acting neutral relay; an energizing circuit closed for said neutral relay whenever the contacts of said polar relay assume either of their polar positions; a series of stepping relays; and an energizing circuit for the first stepping relay of said series including a particular polar contact of said line relay and a back contact of said neutral relay.

25. A centralized traffic controlling system comprising in combination, a line circuit having a polar line relay included therein, a normally deenergized neutral relay having an energizing circuit closed when said polar line relay assumes either of its polar positions, selector apparatus, and a circuit for initiating said selector apparatus closed only if said polar line relay assumes a particular polar position only while said neutral relay still assumes its deenergized position.

26. In a centralized traffic controlling system of the selector type for controlling traffic on railroads, the combination with a line circuit connecting a central office and a plurality of way

stations and including a line relay at said central office and at each of said way stations, of a series of stepping relays in said central office and at each of said way stations, a primary relay in said central office for applying current impulses to said line circuit, energizing circuits controlled by the line relay in said office for causing the stepping relays at said office to be energized sequentially one relay for each impulse on said line circuit, and energizing circuits including front contacts of said stepping relays for intermittently actuating said primary relay.

27. In a centralized traffic controlling system of the selector type for controlling traffic on railroads, the combination with a line circuit connecting a central office and a plurality of way stations and including a line relay at said central office and at each of said way stations, of a series of stepping relays in said central office and at each of said way stations, a primary relay in said central office for applying current impulses to said line circuit, energizing circuits controlled by the line relay in said office for causing the stepping relays at said office to be energized sequentially one relay for each impulse on said line circuit, means for intermittently actuating said primary relay, each actuation being caused by the last of said stepping relays to be energized, and means governed automatically in accordance with a change of traffic conditions at any one of said way stations for causing a first actuation of said primary relay.

28. In a centralized traffic controlling system of the selector type for controlling traffic on railroads, the combination with a line circuit connecting a central office and a plurality of way stations and including a line relay at said central office and at each of said way stations, of a series of stepping relays in said central office and at each of said way stations, a primary relay in said central office for applying current impulses to said line circuit, energizing circuits controlled by the line relay in said office for causing the stepping relays at said office to be energized sequentially one relay for each impulse on said line circuit, means for intermittently actuating said primary relay, each actuation being caused by the last of said stepping relays to be energized, a control lever at said central office for transmitting distinctive control impulses over said selector type system, and means governed in response to the movement of said control lever for causing a first actuation of said primary relay.

29. In a centralized traffic control system for railroads, a control office, a plurality of way stations, a stepping circuit, automatic impulsing means for placing impulses on said stepping circuit, step-by-step means at each of said stations and said control office all operated in synchronism by the application of said impulses to said stepping circuit, and a starting circuit extending between said control office and said way stations capable of being closed at each station only a predetermined time after said stepping circuit has been deenergized.

30. In a centralized traffic control system for control of switches and signals at a field station along the railroad track from a central office by impulses on line wires, a stepping line circuit extending from the control office to the field station, a polarized line relay in said line circuit at the field station, a series of neutral stepping relays at the field station, circuits energized from a local source of current at the field station and controlled by said line relay for energizing said step-

ping relays sequentially one at a time, and means at the station controlled in accordance with the polarity of the first energization of said line circuit for determining whether or not said series of stepping relays shall be operated at all by subsequent operations of said line relay.

31. In a centralized traffic controlling system of the selector type for controlling traffic on railroads; a normally deenergized stepping line circuit connecting a control office and a field station; a line relay at the control office and another at the field station in series in said line circuit; a series of stepping relays at the control office and another series at the field station, each series being controlled by its respective line relay to cause said stepping relays to pick up successively, one for each impulse repeated by such line relay; an impulsing relay for applying an impulse of one polarity or the other to said stepping line circuit for each time it is actuated, when such impulsing relay has been rendered effective to apply the first impulse to said line circuit; a cycle controlling relay for rendering said impulsing relay effective to apply a first impulse to said line circuit; and circuit means for actuating said impulsing relay upon the picking up of each successive stepping relay of said series in the control office.

32. In a centralized traffic controlling system of the selector type for controlling traffic on railroads; a stepping line circuit connecting a control office and a field station; a line relay at the control office and another at the field station in series in said line circuit; a series of stepping relays at the control office and another series at the field station, each series being controlled by its respective line relay to cause said stepping relays to pick up successively, one for each impulse repeated by such line relay; an impulsing relay for applying an impulse to said stepping line circuit for each time it is actuated when such impulsing relay has been rendered effective to apply the first impulse to said line circuit; a cycle controlling relay for rendering said impulsing relay effective to apply a first impulse to said line circuit; circuit means for actuating said impulsing relay upon the picking up of each successive stepping relay of said series in the control office; and means controlled both from the control office and the field station for picking up said cycle controlling relay.

33. In a centralized traffic controlling system of the selector type for controlling traffic on railroads; a stepping line circuit connecting a control office and a field station; a line relay at the control office and another at the field station in series in said line circuit; a series of stepping relays at the control office and another series at the field station, each series being controlled by its respective line relay to cause said stepping relays to pick up successively, one for each impulse repeated by such line relay; an impulsing relay for applying an impulse to said stepping line circuit for each time it is actuated when such impulsing relay has been rendered effective to apply the first impulse to said line circuit; a cycle controlling relay for rendering said impulsing relay effective when said cycle controlling relay is picked up; a slow acting cycle demarking relay controlled by said line relay at the control office so as to be picked up at the beginning of each series of impulses and to be dropped at the end of such series; a pick up circuit for said cycle controlling relay capable of being closed only when said cycle demarking relay is dropped away; a stick circuit for said cycle controlling relay

closed until the last of said stepping relays is picked up, when said stick circuit is once closed; and circuit means for actuating said impulsing relay upon the picking up of each stepping relay successively except the first stepping relay, which first actuation is delayed until the picking up of said cycle demarking relay.

34. In a centralized traffic controlling system of the selector type for controlling traffic on railroads; a polarized stepping line circuit connecting a control office and a field station; a polar line relay at the control office and another at the field station included in series in said polarized stepping line circuit; a series of stepping relays at the control office and another at the field station, each series being controlled by its respective polar line relay to cause said stepping relays to pick up successively, one for each impulse repeated by such polar line relay; an impulsing relay for applying a selected polar impulse to said stepping line circuit for each time it is actuated, when such impulsing relay has been rendered effective; a cycle controlling relay for rendering said impulsing relay effective to apply impulses to said line circuit; and circuit means for selectively actuating said impulsing relay upon the picking up of each successive stepping relay of said series in the control office to determine the polarity of the next impulse on said stepping circuit.

35. In a centralized traffic controlling system of the normally at rest selector type; a normally deenergized line circuit having series of current impulses impressed thereon; a line relay in said line circuit responsive to each impulse of every series; a slow acting relay energized for each impulse on said line circuit as repeated by said line relay so as to be picked up at the beginning of each series and to remain picked up until the end of such series; a series of stepping relays; and pick up circuits for said stepping relays controlled by said line relay so as to be energized successively, one for each impulse on said line circuit, and the pick up circuit for the first stepping relay including a back contact of said slow acting relay.

36. In a centralized traffic controlling system of the normally at rest selector type; a line circuit having series of positive and negative impulses impressed thereon; a three position polar relay in said line circuit actuated to one or another polar position by the positive and negative impulses respectively on said line circuit, and biased to a deenergized neutral position; a slow acting relay energized for each impulse on said line circuit irrespective of the polarity of such impulse, said relay being picked up on the first impulse of a series and sufficiently slow acting to remain picked up until the end of such series; a bank of stepping relays; pick up circuits for stepping circuits of said bank; circuit means controlled by said line relay for successively energizing said pick up circuits, one for each impulse on said line circuit, in accordance with the polar positions of said line relay and dependent upon the proper response of said slow acting relay.

37. In a centralized traffic controlling system of the selector type for controlling traffic on railroads; a normally deenergized stepping line circuit connecting a control office and a remote station; a line relay in said line circuit at the control office; a series of stepping relays controlled by said line relay to cause said stepping relays to pick up successively, one for each impulse on said line circuit; impulsing means for

5 applying a series of current impulses to said line circuit when rendered effective; a cycle controlling relay for rendering said impulsing means effective when such cycle controlling relay is picked up; a slow acting relay energized each time said line relay repeats an impulse on said line circuit, whereby said slow acting relay is picked up at the beginning of a series of impulses and is dropped at the end of such series; 10 a pick up circuit for said cycle controlling relay which can be closed only when said slow acting relay is dropped away; and a stick circuit for said cycle controlling relay including a back contact of the last stepping relay of said series of stepping relays.

15 38. In a centralized traffic controlling system of the selector type for controlling traffic on railroads, a normally open series line circuit connecting a control office and a remote station; a cycle controlling relay for closing said line circuit at the control office and causing a first current impulse to be impressed thereon; a line relay in series in said line circuit at the control office; a series of stepping relays controlled by said line relay to cause said stepping relays to pick up successively, one for each current impulse on said line circuit; a slow acting relay energized each time said line relay repeats a current impulse on said line circuit, whereby said slow acting relay is picked up at the beginning of a series of current impulses and is dropped at the end of such series; impulsing means rendered effective by said cycle controlling relay, only after said slow acting relay has picked up in response to said first current impulse, to remove said first current impulse and impress the remaining current impulses of a series on said line circuit; a pick up circuit for said cycle controlling relay capable of being closed only when 20 said slow acting relay is dropped away; and a stick circuit for said cycle controlling relay including a front contact of said slow acting relay.

25 39. In a centralized traffic controlling system of the selector type for controlling traffic on railroads; a series stepping line circuit connecting a control office and a plurality of field stations; means at the control office for impressing a series of current impulses on said line circuit; a line relay at each of the field stations; a slow 30 acting relay at the first of the field stations energized each time said line relay repeats an impulse on said line circuit, whereby said slow acting relay is picked up at the beginning of a series of impulses and is dropped at the end of such series; a bank of stepping relays at each of the field stations caused to operate step-by-step by its respective line relay when such bank of stepping relays is once initiated; means at the first field station for initiating said bank of stepping relays at that station, said means including a back contact of said slow acting relay; and

means at each of the remaining stations for initiating said bank at such station, said means including a front contact of the last stepping relay in said bank at the next preceding field station.

5 40. In a centralized traffic controlling system of the selector type for controlling traffic on railroads; a series stepping line circuit connecting a control office and a plurality of field stations; means at the control office for impressing a series of current impulses on said line circuit; a line relay at each of the field stations; a slow acting relay energized each time said line relay repeats an impulse on said line circuit, whereby said slow acting relay is picked up at the beginning of a series of impulses and is dropped at the end of such series; a bank of stepping relays at each of the field stations caused to operate step-by-step by its respective line relay when such bank of stepping relays is once initiated; means at the first field station for initiating a bank of stepping relays at that station, said means including a back contact of said slow acting relay; and means for initiating the banks at each of the remaining stations, said means including a line wire connecting that station with the next preceding station and also including a front contact of the last stepping relay in said bank at such preceding station.

10 41. In a selector system of the normally at rest type used for controlling traffic on railroads, the combination of a normally deenergized stepping circuit connecting a control office and a remote station, impulsing means for applying current impulses to said stepping circuit when such impulsing means is initiated, and means for initiating said impulsing means comprising, a stick relay having a front contact which if closed starts said impulsing means into operation, an indicating contact for manifesting traffic conditions, a slow acting repeater relay for directly repeating the position of said indicating contact, a pick up circuit for said stick relay closed whenever said indicating contact and said repeater relay are out of correspondence, and a stick circuit for 15 said stick relay including a contact controlled in response to impulses on said stepping circuit.

20 42. In a centralized traffic controlling system of the normally at rest selector type, the combination with a selector system normally at rest, of means for starting said system comprising, a stick relay having a front contact which if closed starts said system, an indicating contact for manifesting traffic conditions, a slow acting repeater relay for repeating the position of said 25 indicating contact, and a pick up circuit for said stick relay closed whenever and only so long as said indicating contact and said repeater relay are out of corresponding positions.
